(57) **CLAIM**

The ornamental design for a mobile device carrying case, as shown and described.

DESCRIPTION

FIG. 1 is a perspective view of a mobile device carrying case in an open first position with a flap thereof in an open position, showing my new design;

FIG. 2 is a perspective view of the mobile device carrying case of FIG. 1 in a closed second position;

FIG. 3 is a perspective view of the mobile device carrying case of FIG. 1 in an open third position with the flap thereof in a closed position;

FIG. 4 is a front view of the mobile device carrying case of FIG. 1;

FIG. 5 is a back view thereof;

FIG. 6 is a left side view thereof;

FIG. 7 is a right side view thereof;

FIG. 8 is a top view thereof; and,

FIG. 9 is a bottom view thereof.
